UNITED STATES PATENT OFFICE

106,125

DESIGN FOR A DOLL

Isabel Scott and Eugenia Nies, Wheaton, Ill.

Application April 10, 1937, Serial No. 68,670

Term of patent 7 years

To all whom it may concern:

Be it known that we, Isabel Scott and Eugenia Nies, citizens of the United States, residing at Wheaton, in the county of Du Page and State of Illinois, have invented a new, original, and ornamental Design for a Doll, of which the following is a specification, reference being had to the accompanying drawings, forming part thereof.

Fig. 1 is a front perspective view of a doll showing our new design.

Fig. 2 is a side view of the same, partly in perspective.

Fig. 3 is a rear view of the same.

We claim:

The ornamental design for a doll as shown.
EUGENIA NIES.
ISABEL SCOTT.
